UNITED STATES PATENT OFFICE.

CAESAR C. BORCHERS, OF CHICAGO, ILLINOIS.

PACIFIER OR THE LIKE.

1,372,004.

Specification of Letters Patent. Patented Mar. 22, 1921.

Application filed September 20, 1919. Serial No. 325,186.

To all whom it may concern:

Be it known that I, CAESAR C. BORCHERS, a citizen of the United States, residing at Chicago, in the county of Cook and State 5 of Illinois, have invented certain new and useful Improvements in Pacifiers or the like, of which the following is a description.

My invention belongs to that general class of devices known as pacifiers and relates 10 particularly to a jelly type pacifier or nipple. The invention has among its objects the production of a device of the kind described; that is simple, convenient, durable, efficient, attractive, sanitary and satisfactory 15 for use wherever found applicable. Many other objects and advantages of the construction herein shown and described will be obvious to those skilled in the art, from the disclosure herein given.

20 To this end my invention consists of the novel construction, arrangement and combination of parts herein shown and described and more particularly pointed out in the claims.

25 In the drawings, wherein like reference characters indicate like or corresponding parts,

Figure 1 is a perspective view of a pacifier,

30 Fig. 2 is a sectional view through the same,

Fig. 3 is a sectional view through the cap 10 before securing in place, and

Fig. 4 is a plan view of the same.

35 Referring to the drawings, 1 represents a body; for example, a jelly ordinarily made up of gelatin and other constituents which is incased in a covering 2 of rubber or the equivalent. Parts 1 and 2 are arranged on

40 a plate 3 provided with an opening 4 therethrough, through which the open end 5 of the casing 2 is extended. Plate 3 is of the preferred material and of the desired size and shape. Arranged within the covering 45 or casing 2 at the open end is a button of suitable material, for example, wood, bone, or other material that will hold its shape, the button consisting of a head 6, shank 9 with the end of the shank enlarged as at 8.

50 The head 6 is larger than the opening 4 through the plate, while the enlarged portion 8 is of a size that it may be passed through the opening 4 when assembling the parts. As will be seen from Fig. 2, the head 55 6 is arranged to engage the casing 2 and

substantially lock the same between the head and plate 3.

Arranged over the plate 3 at the back side thereof is a cover or cap 10 which may be flanged as at 11 and seat in a recess 12 in the plate 3. The cap 10 extends upwardly as at 14, the top 16 being preferably dished slightly and cut out and formed with a cross bar 17 so as to provide a loop or opening 18, through which a cord 20 or its equivalent, for example, a wire, ribbon, ring or the like may be passed. In assembling the device, body 1, cover 2, plate 3 and the button are arranged substantially as shown, and cap 10 positioned on the same, the cap being 60 constructed substantially as shown in Fig. 3. With the button pushed back as far as possible, the cover is then crimped, bent, or otherwise formed as at 15, or in an equivalent manner, so as to engage the inner side 65 of the enlarged portion 8 of the shank, thereby rigidly locking the parts together. It may be mentioned that in crimping the part 10 at 15, the same is preferably not 70 perforated in any way so as to cause openings through which dirt and dust or germs may get within the cap. In this connection it will be noted that the end of the button is constructed at 19 so as to closely fit the dished end or top 16 of the cap, and seal 75 the same therat.

When a pacifier is constructed, as described, it is practically impossible for dirt, germs, saliva, or the like, to reach the interior of the cap or the mouth of the cover 2. 80 The device is, therefore, not only extremely rigid and durable, but is sanitary.

Having thus described my invention, it is obvious that various immaterial modifications may be made in the same without departing from the spirit of my invention, hence I do not wish to be understood as limiting myself to the exact construction, arrangement, combination of parts and uses mentioned.

100 What I claim as new and desire to secure by Letters Patent is:

1. In a device of the kind described, the combination with a plate having an opening passing therethrough, a nipple open at 105 one end and arranged with the open end extending through the opening in said plate, a button member having an enlarged portion of a size greater than the opening in said plate disposed within the nipple, the 110

shank of the button projecting through the nipple and having an enlarged head of a size smaller than said enlarged portion, but rigidly connected therewith, and a cap resiliently engaging said enlarged head and co-acting with a surface of the plate to maintain the button, and its nipple, in place.

2. In a pacifier of the kind described and in combination, a plate having an opening therethrough, a suitably filled nipple arranged at one side of said plate with the open end extending through the opening in said plate, a button arranged within the nipple and of a length to project through said opening beyond the open end of the nipple and having an enlarged head, a cap member for the enlarged head of said button, the outer end of said button flared beyond the shank thereof, said cap member crimped to engage the flared end of said button and formed to engage the plate, whereby the button is rigidly maintained in place and the nipple locked against withdrawal between the edge of the opening through the plate and the head of the button.

3. In a pacifier of the kind described and

in combination, a plate provided with an opening therethrough, a nipple consisting of a body and a cover arranged thereover, said cover open at one end and projected through the opening in said plate, a button consisting of an enlarged portion and shank and an enlarged head smaller than said enlarged portion, the said enlarged head being of a size sufficient to pass through said opening, a cap member mounted on the plate and covering the enlarged head of said button, said cap member formed to engage the inner side of the enlarged head and rigidly maintain the head of the button in position to engage the cover of the nipple about the edge of the opening, said cap member formed at the outer end of the shank to tightly fit the end thereof, and provided with means for securing a cord thereto.

In testimony whereof, I have hereunto signed my name in the presence of two subscribing witnesses.

CAESAR C. BORCHERS.
